Primary Examiner — Karen E. Eldridge Powers*Assistant Examiner* — Jasmine Mlinarcik(74) *Attorney, Agent, or Firm* — Taylor English Dumas LLP(57) **CLAIM**

We claim the ornamental design for a hat with a curved thick brim, as shown and described.

DESCRIPTION

FIG. 1 is a perspective view of the claimed design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof; and,

FIG. 8 is a perspective view of the claimed design as worn by a user in one embodiment.

The broken line lettering illustrates environmental structure and forms no part of the claimed design. In FIG. 8, the person illustrated in dot-dash broken lines is environmental subject matter included to assist in showing how the design may appear when worn and forms no part of the claimed design.
